UNITED STATES PATENT OFFICE.

CHARLES B. ANDREWS, OF HIGH BRIDGE, NEW JERSEY, ASSIGNOR TO TAYLOR-
WHARTON IRON AND STEEL COMPANY, OF HIGH BRIDGE, NEW JERSEY, A COR-
PORATION OF NEW JERSEY.

DIPPER-TOOTH.

1,234,114.

Specification of Letters Patent. Patented July 24, 1917.

Application filed April 27, 1914. Serial No. 834,561.

To all whom it may concern:

Be it known that I, CHARLES B. ANDREWS, a citizen of the United States, residing at High Bridge, in the county of Hunterdon and State of New Jersey, have invented the following described Improvements in Dipper-Teeth.

The invention is an improved reversible point for the teeth of steam shovel dippers and other excavating apparatus, the object 10 being to increase the proportion of metal contained in such points that is to be worn away in useful service and diminish the proportion required for attaching the point 15 to its base or support.

The drawings illustrate the preferred form of the invention,

Figure 1 being a side elevation of a tooth point and base with a part of the base 20 broken away;

Fig. 2 a section of Fig. 1, on line II—II;

Fig. 3 a perspective view of the point alone;

Fig. 4 a perspective view of the end of 25 the base for such point.

In these figures the body or base of the tooth is indicated at 1, and may be integral with the lip 2 of a steam shovel dipper or connected to it or to any other excavating 30 apparatus in any suitable way. The point fitting on the forward end of the base is symmetrically formed and reversible so that when worn off on its lower side it can be removed and reattached to the base with the 35 other side down, the effective sharpness being thus preserved, and by occasional reversal of the point, the apex or cutting edge thereof can be preserved in substantial coincidence with the axis *a—b* of the tooth, so 40 that the cutting edge will always be maintained at a desired angle with reference to the dipper. The means on the point which form the joint between it and the base, are symmetrically disposed thereon with respect 45 to the said axis *a—b*, but the means on the base, which are complementary to the point, are unsymmetrical to said axis and so arranged that the seating of the point thereon must take place in a direction which is inclined to the said axis, as will later appear.

The joint-forming means comprise a vertical slot formed between two similar nose portions 3, which project integrally from the end of the base, and are each tapered or 55 pointed with an angle which is determined

by the conditions of use. It is known in the operation of steam shovels that the points of the teeth tend to wear away (on their lower sides) in a plane or surface which lies at substantially the same angle to the axis of 60 the tooth in all kinds of shovels. Such an angle is approximated by the angle between the line *c—d* in Fig. 1, and the axis *a—b*, and it is this angle that determines the angle of taper of the nose portions 3. The 65 lower faces of the nose portions are made parallel with the line of wear *c—d*, and the upper surfaces are disposed symmetrically with reference to the axis *a—b*, so that the angle between the upper and lower surfaces 70 of the said nose portions may be said to equal approximately twice the angle which the wearing surface takes to the axis of the point as a whole.

On their proximate faces the two tapered 75 nose portions 3 are provided with two sets of mortise grooves marked 4 and 5, respectively, and these grooves are both substantially parallel to the line *c—d* and the lower 80 faces of the nose portions.

The point is comprised of two divergent arm or wing portions 6, cast or otherwise formed integrally with a web 7, which ties the wings together. The exterior faces of the portions 6 may be at any desired angle 85 and are desirably symmetrical with the axis *a—b* when the point is new. The interior faces are symmetrical with reference to the said axis, and the angle between them is the angle of the nose portions 4 upon 90 which they are adapted to fit and thrust. The web 7 enters and fits the slot between nose portions and for this purpose is provided with integral lugs marked 8, 9, 10 and 11, respectively, there being one lug or set 95 of lugs on each side of the web and symmetrically disposed thereon. These lugs constitute tenon members for the mortise groove formation of the base, and by reason of their symmetrical arrangement are adapted 100 to engage and fit the base, irrespective of which side of the point may be uppermost. Thus, in the case illustrated, the two lugs 8 and 10 being in line can be entered into the mortise groove 4, and the lugs 9 and 11 being 105 also in line, can be entered into the mortise groove 5, thus bringing the point to its full seat on the base. On reversal, the lugs 10 and 11 can enter the groove 4, and lugs 8 and 9, the groove 5, from which it will be 110

seen that each of the lugs shown, together with one of two others, may form a tenon member to coöperate with one of the mortise grooves in the base, and it will be evident that it is not of consequence how many of such lugs be formed in line to form such tenon members. In the present case I have shown four and find that number to be satisfactory. The lug 9, it will be noted, engages the same mortise groove 5, in both positions of the point, in one case its side 9^a being engaged with the bottom of the mortise groove, and in the other case its side 9^b being engaged with the bottom of the same groove. The shape of the lug and particularly of the sides 9^a and 9^b, is such as to provide a proper bearing upon the wall of its groove in both positions of reversal. In the present case the grooves are squared at their bottoms and rounded at their tops, and the tenon lug 9, as well as the others, is correspondingly shaped, each having two flat faces and two rounded faces. In both positions the point is fitted on the base by sliding the lugs into the mortise grooves, until the wings 6 of the point seat on the nose portions 3; whereupon a fastening bolt 12 is passed through the parts to lock the point in place. The thrust of the point on the base is withstood principally by the bearing of the wing portions 6 upon the nose portions 3, the spreading of the wings being prevented by the web, and shearing strains on the bolt being prevented by the interlocking mortise connection, as well as by the wings, since the principal thrust is in the direction of the line of wear. The metal of the point, reversed from time to time, wears away parallel with the inner faces of the wing portions 6 and until such portions become so thin, or the cutting edge becomes so obtuse, as to be no longer serviceable. The remaining metal, consisting practically of nothing but joint, may then be scrapped with minimum of loss in the form of waste.

It will be observed from the foregoing description that the principle of my invention involves the application of a reversible mortise and tenon joint to the nose of a tooth base, the direction of the joint approximating the line of wear on the point and being in oblique relation to the axis thereof.

55 I claim:

1. A tooth of the kind described, comprising a base having an approximately triangular joint portion symmetrical to the longitudinal axis, and a point having a complementary joint portion adapted to fit reversibly upon the joint portion of the base, said joint portions being formed with lateral

mortise and tenon joints which are disposed to engage in either position of the point and the mortises whereof extend at an angle to 65 the axis and approximately parallel to the line of wear of the point.

2. A tooth of the kind described, comprising a base having an approximately triangular, vertically-slotted joint portion symmetrical to the longitudinal axis, and formed in the faces of its slot with mortises extending at an angle to the axis and substantially parallel with the bottom of the joint portion, and a reversible point having a web 70 to enter said slot and top and bottom wings to embrace the joint portion of the base, said web having a plurality of rows of projections arranged at the same angle to the axis as the mortises in the base. 80

3. A tooth of the kind described, comprising a base and a point, said base provided with several parallel mortise grooves in oblique relation to the axis of the point and said point being provided with several 85 tenon members adapted for reversible engagement with the said grooves.

4. A tooth of the kind described, comprising a base having two nose portions with a slot between them and a plurality of mortise grooves formed in the slot substantially parallel with the lower side of the nose portions, in combination with a reversible point for such base provided with wing portions adapted to fit the nose portions, a web adapted to fit the slot, and sets of tenon projections on opposite sides of the web, different groups of which are adapted to engage different mortise grooves in the base according to the position of the point thereon. 100

5. A tooth of the kind described, comprising a base and a point, said base being formed with tapering nose portions separated by a vertical slot and having mortise grooves formed in the sides of said slot in 105 oblique relation to the axis of the point, and said point having wing portions to fit the nose portions and a connecting web portion provided with tenon members capable of reversible engagement with said grooves. 110

6. In a tooth of the kind described, a base having a nose provided with a vertical slot, and a point having wings connected by a web to enter the said slot, the slot being formed with mortise grooves in its sides and 115 the web having tenon projections to engage said grooves.

In testimony whereof, I have signed this specification in the presence of two witnesses.

CHARLES B. ANDREWS.
